UNITED STATES PATENT OFFICE.

CHARLES F. ALLEN, OF HUENEME, CALIFORNIA.

VAGINAL SYRINGE.

SPECIFICATION forming part of Letters Patent No. 701,124, dated May 27, 1902.

Application filed May 27, 1901. Serial No. 62,127. (No model.)

To all whom it may concern:

Be it known that I, CHARLES F. ALLEN, a citizen of the United States, and a resident of Hueneme, in the county of Ventura and State 5 of California, have invented a new and Improved Vaginal Syringe, of which the following is a full, clear, and exact description.

My invention relates to a vaginal syringe. The purpose of the invention is to provide a 10 syringe modeled in accordance with the anatomical curve of the vagina and of such size, shape, and length as to facilitate its introduction and prevent injury to the delicate organs, and, further, to so construct the syringe 15 that when placed in position it will completely seal the entrance into the vagina, so that the liquid introduced from an elevated fountain, for example, will accumulate in the vaginal cavity and will expand the cavity to its full- 20 est capacity and the material be held there for any length of time in close contact with the entire diseased surface and afterward expelled through an especially-designed outlet, and, further, to so construct the syringe that 25 after the same has been in use for some time and has become unsanitary it may be easily and quickly taken apart for the purpose of cleansing.

The invention consists in the novel construction and combination of the several parts, as will be hereinafter fully set forth, and pointed out in the claims.

Reference is to be had to the accompanying drawings, forming a part of this specification, 30 in which similar characters of reference indicate corresponding parts in all the figures.

Figure 1 is a side elevation of the improved syringe. Fig. 2 is an outer end view thereof, and Fig. 3 is a longitudinal section through 40 the syringe.

The syringe consists of a frame A, preferably made of hard rubber, and a pliable or flexible body B, terminating at its inner end in a tip C. The frame A consists of a front 45 plate 10, which, as shown in Fig. 2, is usually of oval shape, and this front plate is provided with a marginal bead 11, as is best shown in Fig. 3. A tubular stem 12 is curved upward from the rear face of the plate 10 at its central portion, the curve of the stem 12 being 50 made to conform substantially to the natural curve of the vagina. Near the rear end of the

tubular stem 12 an exterior collar 13 is preferably formed, and the stem 12 is provided with an extension 14 at the front of the plate 55 10, which extension receives the threaded end of a plug 15, to which plug a flexible hose 16 is attached, adapted for connection with an elevated fountain of any description.

A drain-plug 17 is secured in the front plate 60 10 of the frame at or near the bottom portion of the said plate. This drain-plug 17 is given a downward inclination and is adapted for connection with the offtake-hose 18, the said hose being intended to carry off the liquid 65 from the syringe after the liquid has served its purpose. The body portion B of the syringe is of soft rubber and is of conical shape, and the tip C constitutes an integral portion of the inner end of the body B, and this tip is 70 given an upward curvature. The body and tip, as stated, are made of soft rubber of different degrees of thickness and flexibility to suit the various conditions and requirements, the tip C being of much greater thickness 75 than the body portion B.

The outer end of the body portion B is provided with a marginal rib 19, and this portion of the body is sprung over the rib 11 of the plate 10, and the rib of the body engages 80 with the outer face of the plate within the line of the marginal rib 11 of the plate, so that the body is held in liquid-tight engagement with the front plate 10 of the frame.

The tip C is provided with an internally 85 formed neck 20 at its inner end, and the end of this neck is adapted to engage with the rib 13 on the tubular stem 12 of the frame when the rear end of the said stem is introduced into the forward end of the tip. The tip C 90 is provided with series of apertures or openings 21, whereby liquid which passes through the stem 12 into the tip may escape through the said apertures 21 into the vagina, and the liquid escapes from the vagina through openings 22, which are made in the body B, preferably adjacent to the tip C, and the liquid from the chamber in the body passes out through the medium of the drain-plug 17. 95

It will thus be observed that the liquid 100 after having been used does not enter the body of the syringe through the same opening which supplies the fresh and unused liquid, but reenters through the independent

openings 22. Therefore the fresh liquid passing through the stem 12 into the flexible tip is not contaminated by the liquid that has once been used. When the flow of liquid is 5 interrupted at the offtake-pipe 18—as, for example, through the medium of a pinch-cock or its equivalent—the liquid will be confined in the vagina, causing it to expand or distend, smoothing out the many folds and 10 allowing the liquid to penetrate between the folds, and, in fact, reach the entire surface of the mucous membrane.

It will be observed that the body of the 15 syringe may be removed from the frame and turned inside out and thoroughly cleaned, rendering the syringe perfectly hygienic and antiseptic.

Having thus described my invention, I 20 claim as new and desire to secure by Letters Patent—

1. A vaginal syringe, consisting of a rigid frame comprising a front plate provided with a marginal bead, a tubular inlet-stem, and a drain-outlet, and a body of flexible material 25 terminating in an apertured tip of greater thickness than the material of the body, the said body being of conical shape, the forward end of the body being arranged to be sprung over the marginal bead of the front plate, as 30 described.

2. In a vaginal syringe, a frame comprising a front plate, a tubular stem extending through the front plate to a distance beyond the rear thereof, the rear portion of the stem 35 being curved, and a drain-plug which passes through the said plate, and a conical body of flexible material, provided with a tip also of flexible material but of greater thickness than the body, which tip is closed at its rear end and 40 is in communication with the inner or rear end of the tubular stem, the tip having an upward curve, being provided with series of apertures, the body being likewise provided with apertures, and means substantially as described, for detachably attaching the said 45 body to the front plate of the frame.

3. In a vaginal syringe, the combination, with a frame, consisting of a front plate, an

upwardly - curved tubular stem extending from the rear portion of the front plate, and 50 a drain-plug extending outward from the said front plate, of a body constructed of flexible material and having a conical shape, the forward end of the body being in frictional engagement with the peripheral portion of the 55 plate of the frame, an upwardly-curved apertured tip formed integral with the inner or rear end of the said body, the material of the tip being of greater thickness than the material of the body, the rear or inner end of 60 the tip being closed and its forward end in communication with the said tubular stem and the body being provided with apertures adjacent to the forward end of the said tip, as described.

4. In a vaginal syringe, the combination, with a frame, consisting of a front plate provided with a marginal bead, an upwardly-curved tubular stem extending from the rear portion of the front plate and provided with 70 a collar near its rear end, and a drain-plug extending outward from the said front plate, of a body constructed of flexible material and having a conical shape, the forward end of the body being arranged to be sprung over the 75 bead of the front plate and having a marginal rib adapted to engage with the outer face of the plate within the line of the marginal bead, an upwardly - curved apertured tip formed integral with the inner or rear end of 80 the said body, the material of the tip being of greater thickness than the material of the body, the rear or inner end of the tip being closed and its forward end in communication with the said tubular stem, and the body being provided with apertures adjacent to the 85 forward end of the said tip, for the purpose set forth.

In testimony whereof I have signed my name to this specification in the presence of 90 two subscribing witnesses.

CHARLES F. ALLEN.
